UNITED STATES PATENT OFFICE.

LAWRENCE C. STEELE, OF BALTIMORE, MARYLAND.

METHOD AND APPARATUS FOR HANDLING SHEET MATERIAL.

Application filed October 4, 1924. Serial No. 741,664

My invention relates to a method and to an apparatus for transporting sheet material between stages of treatment and it has for an object to provide for the transfer of such material mechanically to a desired place from a pack resting on edge.

It is customary in tin mills to remove plates from the pickling frames or baskets and place them immediately into suitable receptacles or boshes containing sufficient water to submerge the plates, the plates resting on edge in the receptacles or boshes. As soon as a bosh or a receptacle is filled, it is removed by a crane, or other suitable means, from the vicinity of the pickler to that of a tinning machine; and then the plates are removed from the bosh or receptacle manually and either fed one at a time into the tinning machine or submerged in an auxiliary receptacle carried by the machine from which they are removed one at a time manually or by a mechanical feeder. In accordance with my invention, the manual step of removing sheets from the bosh or receptacle is eliminated when the latter is adjacent to the tinning machine, as I provide a method and apparatus, whereby sheets are mechanically removed one at a time from each pack of a bosh as the latter comes from the pickler and are mechanically fed into the tinning machine. The practice of my invention not only results in cheaper and increased production but also the product is better for the reason that there is a minimum opportunity for sheets to dry precedent to tinning and the marring of sheets or plates incident to manual removal from the boshes is avoided. Accordingly, therefore, it is an object of my invention to provide an improved method and apparatus for the manufacture of tin plate, whereby the step of removing plates or sheets from a bosh and feeding such plates or sheets to a tinning machine shall be effected by machine means.

While my invention finds particular utility in the tin-plate making art, nevertheless it may be used wherever it is desired to remove sheets from a pack resting on edge and to transfer the sheets so removed to a desired machine or place. Hence, it is a further object of my invention to provide a conveying apparatus which shall include a device for adhering laterally to the sheets of a pack for removing them.

A further object of my invention is to provide an extensible and contractible conveyor together with a device carried by the forward end thereof for removing sheets from a pack resting on edge and feeding the sheets so removed to the conveyor.

A further object of my invention is to provide a conveyor pivoted about a substantially horizontal axis and having a feeding device at the forward end thereof for laterally engaging sheets of a pack and to feed them to the conveyor.

A further object of my invention is to provide a conveyor having a movable feeding device at the forward end thereof for feeding sheets of material from a pack resting in water together with means for moving the feeding device to maintain contact thereof with sheets of the pack in succession.

A further object of my invention is to provide a conveyor consisting of stationary and movable portions, each portion having a pair of transverse shafts with conveyor belts or chains engaging pulleys or sprockets carried thereby, the sprockets or pulleys and the chains or belts of one pair of shafts being staggered with respect to those of the other pair and one shaft of each pair of shafts being between the shafts of the other pair, whereby the length of the conveyor may be varied.

A further object of my invention is to provide a conveyor to feed sheet material to a coating machine, for example, a tinning machine, having a depending suction roller at the forward end thereof adapted to be placed between one side of a receptacle, such as a bosh, and the upper portion of a pack of sheets resting in water to remove such sheets and to feed them to the conveyor.

A further object of my invention is to provide a conveyor having feed rolls whose feed passage is transverse to the direction of the conveyor elements, together with a device arranged below the feed rolls for adhering to sheets of a pack resting on edge and moving the sheets up successively to enter between the rolls, a deflector being arranged at the discharge side of the rolls to change the direction of the sheets.

These and other objects are effected by my improved method and apparatus as will appear from the following description and the

accompanying drawings, forming a part of this application, in which:

Fig. 1 is a plan view showing a pair of my feeding devices;

Fig. 2 is a side elevation of one of the feeding devices indicating diagrammatically its relation to a machine to be fed and showing in fragmentary section a receptacle from which sheets are removed;

Fig. 3 is a view, partly in section, taken along the line III—III of Fig. 1 and viewed in the direction of the arrows;

Fig. 4 is a diagrammatic view of the apparatus;

Fig. 5 is a detail view, on a larger scale, showing actuating means for the picking device or suction roller;

Fig. 6 is a fragmentary detail view showing a pair of feed rolls;

Fig. 7 is a longitudinal sectional view of one form of picking device or suction roller;

Fig. 8 is a sectional view taken along the line VIII—VIII of Fig. 7 and viewed in the direction of the arrows;

Fig. 9 is a fragmentary view showing a modified form of suction roller; and

Fig. 10 is a transverse section of the roller shown in Fig. 9.

Referring now to the drawings more in detail for a better understanding of my invention, I show a receptacle 10, for example, a bosh, such as is used in receiving plates from a pickler in a tin mill, having a pack of plates or sheets 11 therein (see Fig. 2) which are to be removed by conveyor apparatus, at 12, and transferred to the feeding device 13 of a machine, for example, a tinning machine. My invention is concerned largely with the conveyor apparatus and the organization and improved method incorporating such apparatus, or apparatus capable of functioning in a similar manner, whereby sheets of a pack resting on edge may be removed in succession and fed to a machine, thereby avoiding the manual step of removing such sheets from the pack as is customary practice.

The conveyor, at 12, carries at its forward end a picking device, at 14, which may be lowered into position between one side of the receptacle or bosh 10 and the upper portion of a pack of sheets or plates 11, the pack being so arranged as to leave a space for the entrance of the picking device. The picking device engages sheets of the pack in succession and lifts them for passage between a pair of feed rolls 15 and 15' also carried by the conveyor. Deflectors 16 are arranged at the discharge side of the feed rolls 15 and 15' in order to deflect sheets toward moving elements of the conveyor, the latter conveying the sheets to the place or machine where they are to be treated or operated upon.

The conveyor is contractible and extensible in order that the picker means, at 14, may be maintained in contact with the sheets of a

pack in succession, and it is capable of being raised and lowered in order that the picking device may be brought into position between a pack and a side of a receptacle and in order that a receptacle or bosh may be removed when emptied.

The conveyor consists of a primary frame 17 which is pivotally connected, at 18, to any suitable support or standard 19, and a secondary frame 20 which is guided by and movable with respect to the primary frame 17. The primary frame 17 is of sufficient length so that, when lowered, it may extend across a bosh and it is provided with upper and lower tracks for upper and lower guide rollers 21 and 22. The secondary frame 20 has depending therefrom the picking device, at 14, already referred to.

The primary frame 17 carries a rear shaft 23 and an intermediate shaft 24 provided with aligned pairs of sprocket wheels 23' and 24' over which engage conveyor chains 25. The secondary frame has rearward and forward shafts 26 and 27, respectively, provided with aligned pairs of sprockets 26' and 27' about which are engaged conveyor chains 28. The rear shaft 26 of the secondary frame is arranged between the shafts 23 and 24 of the primary frame and the pairs of sprockets 23' and 24' and 26' and 27' are staggered so that the secondary conveyor device may telescope into and out of the primary conveyor device without interference. To this end, also, the side members 20' of the secondary frame 20 extend sufficiently above the side members 17' of the primary frame so as not to interfere with the intermediate shaft 24 of the primary frame.

The secondary frame 20 carries a pair of feed rolls 15 and 15', the picking device 14, and the deflector 16 for sheets. The roller 15 is preferably made in sections and mounted on the shaft 27 so as to provide spaces for the sprockets 27'.

The picking or suction roller device, at 14, is preferably of the type disclosed and claimed in my Patent No. 1,057,183, dated March 25, 1913, it comprising an inner stationary cylinder 32 and an outer rotative cylinder 33, the stationary cylinder having trunnions 34 and 35 secured in place with respect to brackets 36 and 37 depending from and secured to the side members 20' of the secondary frame 20. The stationary cylinder 32 is hollow and provides a suction chamber 38 communicating by way of the passage 39 in the hollow trunnion 35 with a conduit 40 leading to any suitable suction device, such as a pump. The stationary cylinder 32 is provided with a longitudinal slot 41 which is arranged to face the sides of sheets to be removed. The rotatable cylinder 33 is provided with bearing portions 43 and 44 which fit the journal portions 34 and 39, respectively, the bearing portion 44 being elongated

gated and having an actuating sprocket 45 keyed thereto. The cylinder 33 is of a foraminous character and it is preferably provided by having perforations 46 extending 5 through the wall thereof. With this apparatus, it will be apparent that, as the perforations 46 register with the longitudinal slot 41, the state of suction existing in the chamber 38 is manifested externally of the rotative member 33 through the registering perforations 46, thereby exerting a suction or adhering effect upon the sheets 11 with which the roller contacts. Rotation of the outer cylinder 33, therefore, serves to bring successive 15 perforations 46 into registry with the slot 41, thereby exerting upon a sheet a rack-like action and serving to elevate it for passage between the feed rolls 15 and 15'.

In order that the suction roller just referred 20 to may act to raise the sheets it should be biased or tend to move into contact with sheets of the pack as they are successively removed. To this end, I provide a drive chain 47 which engages about the driving 25 sprocket 48 carried by the drive shaft 23 and about an idler sprocket 49 carried by an end cross bar 50 of the primary frame 17. The lower side of the chain is arranged to move in the direction of the arrow as indicated in Fig. 5. The lower side of the chain 47 passes over an idler sprocket 51, downwardly, then loops about the sprocket 45 carried by the elongated bearing portion 44 of the rotative cylinder 33, then extends upwardly, and passes over an idler sprocket 52. With this arrangement, it will be apparent 30 that the tension in the lower side of the chain 47 is effective, not only to turn the rotative cylinder 33 in the proper direction, but also to move the secondary frame, with the depending suction roller device, at 14, in such 35 a direction that the rotative cylinder may be maintained in contact with the sheets 11 of the pack as they are successively removed.

Should the action of the sprocket gearing just referred to not be sufficient to develop the desired degree of pressure of the cylinder 33 against the sheets of a pack, such pressure may be augmented by an adjustable 50 counterweight 53 connected to a cord 54, passing over a sheave 55 at one end of the primary frame 17, and connected preferably at a midpoint of an end cross bar of the secondary frame 20.

The feed rollers 15 and 15', the roller 15 being made in sections and carried by the shaft 27, are actuated, respectively, by sprockets 56 and 57 engaging with the top side of the drive chain 47, such drive chain 55 passing under the sprocket 57 and over the sprocket 56. It will, therefore, be seen, that the shaft 23 actuates all of the moving parts, the conveyor chains 25 being directly driven thereby, and the conveyor chains 28, the suction roller device, at 14, and the feed rolls

15 and 15' being driven by the drive chain 47.

The secondary frame 20 is preferably provided with suitable deflector devices 58 and 59 in order to assure that sheets moved upwardly by the suction roller shall enter between the feed rolls 15 and 15', the deflector members 58 being arranged substantially vertical and tangent to the surface of the perforated cylinder 33.

To assure the entry of sheets 11 elevated by the suction roller device, at 14, between the feed rolls 15 and 15', I prefer to have these rolls so mounted that they may be adjusted to and fro with respect to the suction roller. Referring to Figs. 5 and 6, it will be seen that the shaft 27 is mounted for rotation in shoes 60 movable with respect to upper and lower guides 61 and 62 carried by the secondary frame 20. In like manner the shaft 57', for the roll 15' and the sprocket 57, is mounted in shoes 63 also movable between the guideways 61 and 62. The shaft 27 may be moved longitudinally of the frame 20 by adjusting the set screws 64 having threaded connection with brackets 65 carried by the frame 20 and bearing against the shoes 60. As tension of the conveyor chains 28 would resist movement of the shaft 27 in one direction and as movement of such shaft in the other direction would result in such chains sagging, it is desirable that means shall be provided for adjusting the shaft 26 longitudinally with respect to the frame 20 whenever the shaft 27 is adjusted. Consequently, I show the shaft 26 and the guide rollers 21 and 22 at that end of the frame 20 carried by a bracket 66 which is adjustable with respect to the side members 20' of the frame 20 by a suitable screw 67.

If the position of the roll 15 is varied by adjustment of the screws 64, the roll 15' will be maintained in contact with the roll 15, as such roll 15' is biased in that direction by compression springs 68 which engage at one end abutments 69 on the shoes 63 and which abut at the other ends nuts 70 carried by the screws 71, which are threaded to bosses or projections 72 carried by the secondary frame 20. The springs 68 maintain contact of the roll 15' with the roll 15 and the pressure of contact may be varied by adjusting the nuts 70 along the screws 71. If the rolls are moved to such an extent that the screws 71 would either be in the way or would not afford sufficient range of movement for the nuts 70 to obtain the proper compression of the springs 68, then the screws 71 may be adjusted with respect to the bosses or projections 72.

While I prefer to use a suction roller of the type referred to in my patent aforesaid and as illustrated in Figs. 7 and 8, it will be understood that other types of rollers may be used for this purpose. For example, in Figs. 9 and 10, I show a roller 74 having a

rubber facing 75 provided with vacuum cups 76. If such a roller is used and placed into contact laterally with sheets of a pack, as indicated in Fig. 2, the cups 76 would adhere to the sheets and raise them for passage between the feed rolls 15 and 15'.

I show the conveyor mechanism, at 12, adapted to feed sheets or plates into selective feeding mechanism, at 77, of the type disclosed and claimed in my application, Serial No. 705,407, filed April 9, 1924. It will be apparent to those skilled in the art that the conveyor chains 25 of the primary frame 17 might deliver sheets to any suitable mechanism for feeding such sheets into a machine.

The supporting standard 19 and the pivotal connection 18 with respect to the primary frame 17 may be located along the latter at such a position that the portions of the pivoted structure at either side of the pivotal connection shall be in substantial balance, whereby the primary frame 17 may be raised and lowered with a minimum of effort and whereby, when such frame is raised, it will stay up while one bosh is being removed and another is being inserted. As shown in Fig. 4, if the primary-frame side of the pivoted structure should over-balance the other side, a counterweight 78 supported by a cord 79 passing over a sheave 80 and connected to the outer end of the primary frame 17 may be used to place the pivoted structure in substantial balance.

From the structure described, the operation of apparatus made in accordance with my invention will be apparent. A bosh or receptacle 10 is located adjacent to a pickling device from which pickled sheets are removed and placed in the bosh in the form of packs resting on edge. The packs are so arranged as to leave a space at one side of the bosh in order that a suction roller or picking device, at 14, may be inserted between the pack and one side of the bosh as indicated in Fig. 2. After being filled in this manner, the bosh is transported by a crane or other suitable device from the region of the pickler to that of a machine to be fed. The conveyor mechanism, at 12, will be in an elevated position before the bosh is located therebelow; and, when the bosh is in position, the conveyor device, at 12, is pulled down so that the suction roller, at 14, shall enter the space between one wall of the bosh 10 and the upper portion of the pack of sheets 11, downward motion of the conveyor device, at 12, for this purpose being limited by a suitable stop 81 connected to the outer end thereof. The suction roller adheres to the sheets and moves them up to pass between the feed rolls 15 and 15' in succession; and, from the feed rolls 15 and 15' the sheets are deflected by the members 16 in order that they may fall over onto the conveyor chains 28 of the secondary frame. The conveyor chains 28 pass the

sheets rearwardly and then they are taken by the conveyor chains 25 of the primary frame and carried to any suitable feeding mechanism for passage between the feeding device 13 of any suitable machine to be fed. After all the sheets are removed from a bosh, the conveyor device, at 12, is tilted upwardly to remove the picking device or suction roller, at 14, so that an empty bosh may be removed and another bosh with packs of sheets therein may be placed in position.

The foregoing description relates in detail to a single conveyor device, at 12. In Figs. 1 and 3, two such conveyor devices, at 12, are shown arranged side by side for the reason that the ordinary bosh is long enough to accommodate two packs of sheets. As these conveyor devices, at 12, are duplicates, no further description is deemed to be necessary.

From the foregoing it will be apparent that I have devised a method and apparatus whereby only one manual handling of sheets takes place from the time they enter the pickler until they come out of the tinning machine tinned, and that manual step is the removal of batches of plates from a pickler frame and placing them in a bosh. This is advantageous not only from the standpoint of cheaper and more rapid production but also the product is better for reason that there is less opportunity for "greening" or drying and the scratching or marring of plates incident to manual removal from a bosh is avoided.

While I have shown my invention in but one form, it will be obvious to those skilled in the art that it is not so limited, but is susceptible of various other modifications and changes without departing from the spirit thereof, and I desire, therefore, that only such limitations shall be placed thereupon as are imposed by the prior art or as are specifically set forth in the appended claims.

Having thus described the invention what I claim as new and desire to secure by Letters Patent is:

1. In apparatus for conveying sheets from a pack resting on edge, the combination of a frame, a conveyor movable endwise of the frame and including movable conveyor elements, a depending roller carried by the forward end of the conveyor and adapted to contact laterally with the sheets and to adhere thereto with sufficient force to raise the sheets and to feed them to the conveyor, a driving sprocket for the roller, a pair of sprockets on the conveyor, a sprocket chain having one side engaging over the conveyor sprockets, passing therebetween, and looping over the roller sprocket, whereby the tension in said chain is effective to pull the roller into contact with the sheets.

2. In a conveyor for conveying sheets from a pack resting on edge and submerged in liquid in a receptacle, the upper portion of

the pack being spaced from one side of the receptacle, the combination of a first frame pivotally mounted about a substantially horizontal axis, a pair of shafts extending transversely of the frame, one of said shafts being disposed at the rear of said frame and the other shaft being disposed intermediately thereof, aligned pairs of sprocket wheels carried by the shafts, conveyor chains engaging about the sprocket wheels, a second frame movable longitudinally with respect to the first frame, a second pair of shafts disposed transversely of the second frame, the rear-most of the latter shafts being disposed between the shafts of the first pair, aligned pairs of sprocket wheels carried by the second pair of shafts and staggered with respect to the aligned pairs of sprocket wheels of the first pair of shafts, conveyor chains engaging over the sprocket wheels of the second pair of shafts, bearings depending from the forward end of the second frame, a suction roller journaled in said bearings and adapted to fit into the space between the upper portion of said pack and one side of the receptacle for engaging and raising the sheets thereof in succession, a pair of feed rolls carried by the second frame forwardly of the foremost of the pair of shafts carried thereby and adapted to receive sheets raised by the sheet feeding device, means carried by the second frame for deflecting sheets from the feed rolls to the conveyor chains of the second frame, a pair of fixedly spaced sprockets mounted on the first frame, a pair of idler sprockets carried by the second frame arranged above the axis of the sheet feeding device, a sprocket wheel included in the sheet feeding device, sprocket wheels carried by the feed rolls, and a sprocket chain one side of which passes over and between the idler sprockets and loops the sprocket wheel of the sheet feeding device and the other side of which passes under one and over the other of the feed roll sprocket wheels and over said sprockets mounted on the first frame, whereby movement of said chain operates the conveyor chains, the feed rolls and the sheet feeding device in unison.

4. In apparatus for conveying sheets from a pack comprising a primary frame, a secondary frame movably mounted on the primary frame, a traveling conveyor mounted on the primary frame, a traveling conveyor mounted on the secondary frame, a sheet feeding device carried by the latter frame adapted to contact with the outside sheet of the pack, and an endless sprocket chain mounted on the primary frame for driving the conveyors and the sheet feeding device.

5. In apparatus for conveying sheets from a pack comprising a primary frame, a secondary frame movably mounted on the primary frame, a traveling conveyor mounted on the primary frame, a traveling conveyor mounted on the secondary frame, a sheet feeding device carried by the latter frame adapted to contact with the outside sheet of the pack, a pair of fixedly spaced sprockets mounted on the primary frame and an endless sprocket chain mounted on said sprockets for driving the conveyors and the sheet feeding device.

6. In apparatus for conveying sheets from a pack, the combination of an extensible and contractible conveyor tiltable about a substantially horizontal axis and a sheet feeding device carried by the endwise movable end of the conveyor for contacting laterally with the sheets and feeding them progressively to the conveyor.

7. In apparatus for conveying sheets from a pack, the combination of an extensible and contractible conveyor, a sheet feeding device carried by the endwise movable end of the conveyor for contacting laterally with the sheets and feeding them progressively to the conveyor, means for driving said device and

means co-acting with said driving means for pressing said device into contact with the sheet.

8. In apparatus for conveying sheets from a pack comprising a conveyor including a movable element, a sheet feeding device from said movable element adapted to contact with the outside sheet of the pack for removing said sheet and feeding it to the conveyor, driving means for operating the sheet feeding device, and means co-acting with said driving means for moving said sheet feeding device into contact with the sheets.

9. In apparatus for conveying sheets from a pack comprising a conveyor pivotally mounted on a substantially horizontal axis, said conveyor including a movable element, a sheet feeding device depending from said movable element adapted to contact with the outside sheet of the pack for feeding said sheet to the conveyor, driving means for the sheet feeding device, and means co-acting with said driving means for moving said feeding device into contact with the sheet.

10. In apparatus for conveying sheets from a pack comprising an extensible and contractible conveyor including a movable element, a sheet feeding device depending from said movable element adapted to contact with the outside sheet of the pack and for feeding it to the conveyor, driving means for said sheet feeding device and means co-acting with said driving means which, in operation, tends to extend the conveyor to maintain said feeding device in contact with the sheet.

11. In apparatus for conveying sheets from a pack comprising a primary frame, a secondary frame movably mounted on the primary frame, a traveling conveyor mounted on the primary frame, a traveling conveyor mounted on the secondary frame, a sheet feeding device carried by the latter frame adapted to contact with the outside sheet of the pack, a pair of fixedly spaced sprockets mounted on the primary frame, a sprocket adapted to drive said feeding device, a pair of sprockets mounted on the secondary frame, and a sprocket chain passing over the pair of sprockets on the primary frame, over and between the sprockets mounted on the secondary frame, and looping about the sprocket for driving the feeding device, whereby, in operation, the tension of the sprocket chain is effective to move the secondary frame in such a direction as to maintain contact between the feeding device and the sheets.

12. In apparatus for conveying sheets from a pack comprising a primary frame, a secondary frame movably mounted on the primary frame, a traveling conveyor mounted on the primary frame, a traveling conveyor mounted on the secondary frame, a sheet feeding device carried by the latter frame adapted to contact with the outside sheet of the pack, an endless sprocket chain mounted on the

primary frame for driving the conveyors and the sheet feeding device, and means co-acting with said driving means for moving the secondary frame longitudinally with respect to the primary frame.

13. In apparatus for conveying sheets from a pack comprising a primary frame pivotally mounted about a substantially horizontal axis, a pair of shafts extending transversely of the frame, one of said shafts being disposed at the rear of said frame and the other shaft being disposed intermediately thereof, aligned pairs of sprocket wheels carried by the shafts conveyor chains engaging about the sprocket wheels, a secondary frame movable longitudinally with respect to the first frame, a pair of shafts disposed transversely of the second frame, the rearmost on the latter shaft being disposed between the shafts of the first pair, aligned pairs of sprocket wheels carried by the second pair of shafts and staggered with respect to the aligned pairs of sprocket wheels of the first pair of shafts, conveyor chains engaging over the sprocket wheels of the second pair of shafts, a sheet feeding device depending from the forward end of the secondary frame adapted to contact with the outside sheets of the pack, a pair of feed rolls carried by the secondary frame adapted to receive sheets raised by the feeding device, means for driving the conveyor chains, the feeding device and the feed rolls, and means co-acting with said means for moving the secondary frame longitudinally with respect to the primary frame.

14. In apparatus for conveying sheets from a pack comprising a primary frame pivotally mounted about a substantially horizontal axis, a pair of shafts extending transversely of the frame, one of said shafts being disposed at the rear of said frame aligned pairs of sprocket wheels carried by the shafts, conveyor chains engaging about the sprocket wheels, a secondary frame movable longitudinally with respect to the first frame, a second pair of shafts disposed transversely of the secondary frame, the rearmost of the latter shafts being disposed between the shafts of the first pair, aligned pairs of sprocket wheels carried by the second pair of shafts and staggered with respect to the aligned pairs of sprocket wheels of the first pair of shafts, conveyor chains engaging over the sprocket wheels of the second pair of shafts, a sheet feeding device depending from the forward end of the secondary frame adapted to contact with the outside sheet of the pack and move the sheets transversely with respect to the pack, a roll carried by the secondary frame forwardly of the foremost of the pair of shafts carried thereby, a roll fixedly mounted on the latter shaft intermediate the sprocket wheels mounted thereon, said rolls constituting feeding rolls adapted to receive

the sheets moved by said feeding device, said shafts mounted on the primary frame extending beyond said frame and each shaft having mounted thereon a sprocket wheel disposed outside the frame, a sprocket chain surrounding the last mentioned sprocket wheels, a driving sprocket wheel also mounted on the extending end of the rearmost shaft which is mounted on the primary frame, an idler sprocket wheel mounted at the forward end of the primary frame, a sprocket for driving the feeding device, a pair of idler sprockets carried by the secondary frame arranged above the axis of the last mentioned sprocket, the foremost shaft mounted on the secondary frame being provided with a sprocket aligned with said pair of idler sprockets, a sprocket wheel fixedly mounted on the foremost roll,

a sprocket chain one side of which passes over and between the idler sprockets and loops the sprocket which drives the feeding device and the other side of which passes around the idler disposed to the forward end of the primary frame and passes between the sprockets mounted on the forward shaft of the secondary frame and said roll respectively and continues around the driving sprocket mounted on the rearmost shaft mounted on the primary frame, whereby the movement of the chain in a certain direction operates the conveyor chains, the feed rolls and the feeding device and causes the latter to maintain contact with the surface of the sheet.

In testimony whereof I hereunto affix my signature this 20 day of September, 1924.

LAWRENCE C. STEELE.
